Primary Examiner—Sandra Snapp

(57) **CLAIM**

The ornamental design for a tailgate receiver and table with chairs combination, as shown and described.

DESCRIPTION

FIG. 1 is a top, front perspective view of the tailgate carrier and table with chairs combination, with the floor of the carrier, post and chairs removed for ease of illustration.

FIG. 2 is a top, front perspective view of the tailgate receiver carrier and table with chairs combination, shown in the table with chairs mode, the chairs in an extended and open position and the table in the raised position; and,

FIG. 3 is a top, front perspective view of the tailgate receiver carrier and table with chairs combination, shown in the carrier mode, with the chairs in the raised position and the table bottom side up and in the lowered position.
